UNITED STATES PATENT OFFICE.

JOHN L. LATTA, OF HICKORY, NORTH CAROLINA.

PUMP.

1,231,624.

Specification of Letters Patent.

Patented July 3, 1917.

Application filed May 24, 1916. Serial No. 99,578.

To all whom it may concern:

Be it known that I, JOHN L. LATTA, a citizen of the United States, residing at Hickory, in the county of Catawba and State 5 of North Carolina, have invented a new and useful Pump, of which the following is a specification.

The present invention appertains to pumps, and relates more especially to pneumatic displacement pumps.

It is the object of the invention to provide a novel and improved pump of such construction and operation that the water can be displaced by a pressure fluid, such as 15 compressed air, and raised the desired height.

It is the object of the invention to provide a pump barrel or cylinder having a check-valved water or liquid inlet, liquid outlet 20 means, pressure fluid inlet and outlet means, and novel means for controlling the flow of the pressure fluid, whereby the barrel or cylinder is alternately filled and discharged with the liquid, the liquid being intermittently displaced from the cylinder by the 25 pressure fluid.

It is also the object of the invention to provide a pneumatic displacement pump which is comparatively simple, compact and inexpensive in construction, which is improved generally in its construction and details, and which will perform its office in a thoroughly practical and efficacious manner.

With the foregoing and other objects in view which will appear as the description proceeds, the invention resides in the combination and arrangement of parts and in the details of construction hereinafter described and claimed, it being understood that 40 changes in the precise embodiment of the invention herein disclosed can be made within the scope of what is claimed without departing from the spirit of the invention.

The invention is illustrated in the accompanying drawing, wherein:

Figure 1 is a vertical section of the pump, taken on the line 1—1 of Fig. 3, portions being broken away.

Fig. 2 is an upper end view of the pump. 50 Fig. 3 is a cross section taken on the line 3—3 of Fig. 1.

At the outset, it might be stated, that the structure is illustrated more or less diagrammatically, since the proportions of the several parts can be changed in many respects, 55 within the scope of the appended claims, to

adapt the pump to various conditions and circumstances.

The pump embodies a vertical cylinder or barrel 1 providing a water chamber, and a 60 cap 2 is secured in any suitable manner upon the upper end of the cylinder 1 and is provided with an upstanding head 3. The lower end of the cylinder 1 is closed by a cap 4 provided with a central upstanding pin or 65 stud 5, and with water or liquid inlet apertures 6 surrounding the stud 5. A disk valve 7 is slideable upon the stud 5 to provide a check valve permitting of the inflow of liquid, but preventing the outflow of 70 liquid, through the apertures 6. The upward movement of the valve 7 is limited by a nut 8 or other stop carried by the stud 5. When the valve 7 gravitates onto the cap 4, it covers the apertures 6, to prevent the 75 escape of water or other liquid from the cylinder through the apertures 6.

The head 3 is provided with a vertical bore 9 providing a pressure fluid outlet, and said head has a counter bore or recess 10 at 80 the lower end of the bore 9. A pressure fluid escape pipe or tube 11 has its lower end engaged with the head 3 to communicate with the bore 9, and can extend upwardly to any suitable point where it is desired to 85 discharge the pressure fluid to the atmosphere. A depending tube 12 has its upper end engaged with the head 3 to communicate with the lower end of the bore 9, and projects downwardly centrally within the recess 90 10, the lower end of the tube 12 providing a valve seat 13. The pressure fluid, when the end of the tube 12 is uncovered, can pass to the atmosphere from the cylinder 1 by way of the tube 12, bore 9 and pipe 11. 95

A vertical tubular housing 14 has its upper end projecting loosely within the recess 10 around the tube 12, and a collar 15 is secured or fitted tightly within the upper end of the housing 14 and is slideable upon the 100 tube 12. A coiled wire expansion spring 16 surrounds the tube 12 and has its upper end secured to the collar 15, said spring 16 being disposed within the housing 14 and being of such a length, that when the housing 14 is 105 raised, the lower end of the spring 16 moves slightly above the valve seat 13.

Disposed loosely within the housing 14 is an upper resilient buoyant ball valve 17 seatable upwardly against the seat 13 to close the 110 end of the tube 12, and the housing 14 is provided with air apertures 18 therein adjacent

the end of the tube 12, or near the upper end of the housing. A second resilient buoyant ball valve 20 is disposed within the housing 14 below the valve 17, and said housing 5 is provided with water apertures 21 therein adjacent its lower end. The valve 20 is seatable upon an annular valve seat 19 engaged within the lower end of the housing 14. The housing 14 is movable vertically or longitudinally of itself to control the discharge of the pressure fluid from the cylinder.

The valve seat 19 is provided with a depending tubular extension 22 provided with opposite leather cups 23 or other packing 15 slidable snugly within an upstanding cylinder 24 and providing a piston working therein. The lower end of the cylinder 24 is attached to a horizontal coupling 25 disposed within the cylinder 1 near the lower end 20 thereof, and said coupling 25 has a passage 26, one end of which communicates with the lower end of the cylinder 24, and the other end of which communicates with the lower end of a tube or pipe 27 which is attached 25 to the coupling 25. The upper end of the pipe 27 is attached to the head 3 to communicate with a discharge passage 28 thereof. A discharge or eduction pipe 29 for the water or other liquid is attached to the head 30 3 to communicate with the passage 28, and can extend to the point where it is desired to discharge the liquid when elevated.

A disk valve 30 is disposed loosely within the cylinder 24 and is seatable upwardly 35 against the extension 22 which provides a seat for said valve 30, the valve 30 having an upstanding stem 31 slidable in a spider or guide 32 with which the extension 22 is provided. The valve 30 is raised under the 40 influence of a spiral spring 33 disposed within the cylinder 24 and confined between the coupling 25 and the confronting face of the valve 30.

The head 3 is further provided with a vertical bore 34 providing a pressure fluid inlet, the lower end of a pressure fluid supply pipe 35 being engaged with the head 3 to communicate with the upper end of the bore 34. The head 3 has a passage 36 extending 45 from the recess 10 to the bore 34 between the ends of said bore, and the head has a passage 37 extending from the lower end of the bore 34 and communicating with the upper end of the chamber within the cylinder. A spool valve 38 is slidable within the bore 34, being slightly loose, to permit of a slight but not excessive leakage of air past said valve. The valve 38 is provided with an annular groove 39 between its ends adapted 50 to register with the passage 36, and the valve has a passage 40 extending from its upper end to the groove 39, while the lower end of the valve is closed. The valve 38 is raised yieldably under the influence of a coiled expansion spring 41 seated upon the lower end

of the bore 34 and supporting said valve, whereby to restore it to normal position after said valve is displaced downwardly.

In operation, the cylinder 1 is submerged in the water or other liquid which is to be elevated, and when the pressure within the cylinder is relieved, the water will flow by gravity through the apertures 6 into the cylinder, the check valve 7 in seating over the apertures 6 preventing the escape of the water through said apertures. Before the cylinder 1 is filled with water, the valves 20-17 gravitate within the housing 14, and as the cylinder becomes filled with water, the water in filling the housing 14, will float the valves and carry them upwardly until the valve 17 is seated against the lower end of the tube 12, thereby preventing the further escape of air from the cylinder by way of the tube 12, bore 9 and pipe 11. Now, if air under pressure or other pressure fluid is admitted into the cylinder, the air flowing from the pipe 35 into the bore 34 and thence through the passage 40, groove 39, passage 36 and recess 10 into the upper end of the cylinder 1. The compressed air will therefore force the water downwardly within the cylinder through the apertures 21 of the housing 14 into the lower end of said housing and thence through the valve seat 19 into the cylinder 24. From the cylinder 24, the water is forced through the passage 26, pipe 27, passage 28 and pipe 29 to the point of discharge, the water being displaced by the air, and being elevated thereby. The air in flowing through the passage 37 into the lower end of the bore 34, will equalize the pressure upon the opposite ends of the valve 38, thus maintaining said valve in normal position. When the water is discharged down to the level of the valve seat 19, the discharge of water is arrested, and after the valve 20 seats the air pressure in the cylinder is reduced as will presently appear. During the time that the water is being ejected from the cylinder, the valve 17 is held seated by the air pressure, but the valve 20 will move downwardly with the level of the water, so that when the level of the water reaches the seat 19, the valve 20 will seat thereon, thereby preventing the further escape of water or the escape of air through the water outlet conduit. Consequently, the unbalanced air pressure in the cylinder 1 upon the housing 14 will force the piston 23 downwardly in the cylinder 24 against the static pressure of the water in pipe 27, and the housing 14 in being moved downwardly will move the upper end of the expansion spring 16 downwardly, thereby bringing said spring under compression upon the valve 17. The valve 17 is held seated by the air pressure, until the housing 14 is moved downwardly a sufficient extent to bring the spring 16 under such tension that

it overcomes the air pressure suddenly, and the spring 16 in expanding by a sharp movement, serves to throw the valve 17 downwardly with considerable force, beyond the range of the rush of air from the cylinder through the tube 12, thus preventing the valve 17 from being sucked back against the seat 13. The downward movement of the housing 14 thus results in the unseating of the valve 17 and the opening of the tube 12, which at once relieves the pressure in the cylinder, since the air will flow to the atmosphere. At the moment that the valve 17 is thrown from its seat, so that there is a sudden exit of air from the cylinder, the air pressure in the passage 37 and lower end of the bore 34 is suddenly relieved, whereby the live air pressure above the valve 38, will force said valve downwardly momentarily, against the tension of the spring 41, whereby the upper portion of the valve 38 will close the passage 36, thereby momentarily preventing the inflow of air into the cylinder, during the time that the air is being discharged. This prevents a wastage of air, and also facilitates the operation of the pump. The valve 38 being moved downwardly will be held in this position for a short time, the water again flowing into the cylinder to raise the valve 17 against its seat for a new operation. In order to withdraw the spring 16 from the seat 13, to allow the valve 17 to seat, the column of water within the water discharge conduit will, assisted by the spring 33, seat the valve 30 against the extension 22, and the weight of the column of water will raise the piston 23 and housing 14, thus lifting the spring 16 to normal position with its lower terminal slightly above the seat 13. During the seating of the valve 17, the spring 41 assisted by the leakage of air past the valve 38, will cause the valve 38 to be gradually moved back to normal position, and as soon as the valve 17 is seated, the operation is repeated. The valve 38 not only prevents the waste of air during the interim of the exhaust of air from the cylinder, but also permits of the free flow of water into the cylinder. It will be noted that the upper end of the valve 38 is subjected to live air pressure at all times, whereas when the valve 17 is unseated, the cylinder pressure being relieved, will relieve the pressure against the lower end of the valve 38, whereby said valve is moved downwardly as above indicated. If there were not a slight leakage of the air past the valve 38, it would be held in displaced position, so that this leakage is essential, to permit the valve 38 to be gradually returned to normal position by the spring 41 in order that the live air will again be delivered into the cylinder at about the time the valve 17 is seated. This leakage of air past the valve 38 can be provided by providing a slightly loose in-

stead of a tight fit between the valve 38 and the walls of the bore 34, allowing a minute leakage of air.

The present pump employs but a single liquid chamber or cylinder which is intermittently filled and discharged by the automatic control of the air. The present pump is adapted admirably for use when a simple and inexpensive pump of this general character is desired.

Having thus described the invention, what is claimed as new is:

1. A pump embodying a chamber having a check valved liquid inlet, a pressure fluid inlet, a pressure fluid outlet and a liquid outlet, means operable for automatically closing the pressure fluid outlet when the liquid level rises to a predetermined point in said chamber and adapted to be held in closed position by pressure fluid, and means operable for moving said means to open position out of range of the pressure fluid flowing through the pressure fluid outlet when the liquid has been forced from said chamber through the liquid outlet.

2. A pump embodying a chamber having a check-valved liquid inlet, a pressure fluid inlet and a pressure fluid outlet, a valve for closing the pressure fluid outlet, yielding means having a liquid outlet and adapted to unseat said valve, and means for closing said liquid outlet when the liquid has been forced from the chamber there-through.

3. A pump embodying a chamber having a check-valved liquid inlet, a pressure fluid inlet, a liquid outlet and a pressure fluid outlet, means for closing the pressure fluid outlet, a movable member having a valve seat through which the liquid flows to the liquid outlet, a buoyant valve seatable upon said seat when the liquid has been forced from the chamber through the liquid outlet, said member being actuated by the pressure fluid when said valve is seated, and said member having means for moving the aforesaid means to open position when said member is moved by the pressure fluid.

4. A pump embodying a chamber having a check-valved liquid inlet, a pressure fluid inlet, a liquid outlet and a pressure fluid outlet, a valve for closing the pressure fluid outlet, a pressure fluid operated member having a valve seat through which the liquid flows when forced from the chamber through the liquid outlet, a buoyant valve seatable upon said seat, and means carried by said member for unseating the first mentioned valve when said member is moved by the pressure fluid.

5. A pump embodying a chamber having a check-valved liquid inlet, a pressure fluid inlet, a liquid outlet and a pressure fluid outlet, means for closing the pressure fluid outlet, a cylinder communicating with the

- liquid outlet and from which the liquid flows to said outlet, a housing having a piston working in said cylinder and valve seats, a valve seatable upwardly against one of said seats; a buoyant valve within the housing seatable downwardly against the other of said seats, said housing when moved by the pressure fluid serving to move the aforesaid means to open position.
10. 6. A pump embodying a chamber having a check-valved liquid inlet, a pressure fluid inlet, a liquid outlet and a pressure fluid outlet, a cylinder communicating with the liquid outlet and from which the liquid flows to said outlet, a housing having a piston working in said cylinder and valve seats, a valve seatable upwardly against one of said seats, a buoyant valve within the housing seatable downwardly upon the other 70 of said seats, and a valve for closing the pressure fluid outlet and unseated when the housing is moved by the pressure fluid.
15. 7. A pump embodying a chamber having a check-valved liquid inlet, a pressure fluid inlet, a liquid outlet and a pressure fluid outlet, a valve for closing the pressure fluid outlet, and means for unseating said valve when the liquid has been forced from the chamber through the liquid outlet, the last 75 mentioned means including spring means adapted to be brought under tension for unseating said valve by a quick movement to throw it from its seat.
20. 8. A pump embodying a chamber having a check-valved liquid inlet, a pressure fluid inlet, a liquid outlet and a pressure fluid outlet, means for closing the pressure fluid outlet, a member through which the liquid flows from the chamber to the liquid outlet, a second member slidably engaging the aforesaid member and having a valve seat, a buoyant valve seatable upon said seat, the second mentioned member being moved by the pressure fluid when said valve is seated, and the second mentioned member having 80 means for moving the aforesaid means to open position when the second mentioned member is moved by the pressure fluid.
25. 9. A pump embodying a chamber having a check-valved liquid inlet, a pressure fluid inlet, a liquid outlet and a pressure fluid outlet, a valve for closing the pressure fluid outlet, a member through which the liquid flows from the chamber to the liquid outlet, a second member slidably engaging the aforesaid member and having a valve seat, a buoyant valve seatable upon said seat, the second member being moved by the pressure fluid when the second mentioned valve 85 is seated, and spring means movable with the second mentioned member and brought under tension to throw the first mentioned valve from its seat when the second mentioned member is operated by the pressure fluid.
10. A pump having a check-valved liquid inlet, an upper pressure fluid inlet, a liquid outlet and an upper pressure fluid outlet, a tube depending from the pressure fluid outlet and having a seat at its lower end, a cylinder 70 communicating with the liquid outlet and through which the liquid flows to said outlet, a housing whose upper portion surrounds said tube and whose lower end has a piston working in said cylinder and valve seats, a valve within the cylinder seatable upwardly against one of said seats, a buoyant valve within the housing seatable downwardly against the other of said seats, a second buoyant valve within the housing seatable upwardly against the first mentioned seat, and a coiled spring surrounding said tube and having its upper end attached to the housing, said spring being seatable upon the second mentioned buoyant valve when the housing is lowered, to throw said valve from its seat.
11. A pump embodying a chamber having a check-valved inlet, a pressure fluid inlet, a liquid outlet and a pressure fluid outlet, means for closing the pressure fluid outlet, means operated by the pressure fluid for moving said means to open position when the liquid has been forced from the chamber through the liquid outlet, and means operated by the pressure fluid for momentarily shutting off the flow of pressure fluid from its inlet to the chamber during the interim of pressure fluid discharge after the first mentioned means is moved to open position.
12. A pump embodying a chamber having a check-valved liquid inlet, a pressure fluid inlet, a liquid outlet and a pressure fluid outlet, means for closing the pressure fluid outlet, pressure fluid operated means for moving said means to open position when the liquid has been forced from the chamber through the liquid outlet, and a pressure fluid operated valve for the pressure fluid inlet operable to momentarily shut off the flow of pressure fluid into said chamber due to a reduction in the pressure in said chamber after the first mentioned means is moved to open position.
13. A pump embodying a chamber having a check-valved liquid inlet, a pressure fluid inlet, a liquid outlet and a pressure fluid outlet, means for closing the pressure fluid outlet, pressure fluid operated means for moving said means to open position when the liquid has been forced from the chamber through the liquid outlet, and a controlling valve for the pressure fluid inlet and subjected at opposite ends to live and chamber pressures whereby the valve is normally held in open position, said valve being moved to closed position by the pressure fluid due to a reduction in pressure in said chamber by the movement of the first mentioned means to open position.

14. A pump embodying a chamber having a check-valved liquid inlet and a head, liquid outlet means, pressure fluid outlet means, means for closing the pressure fluid outlet means, means for moving said closing means to open position when the liquid has been forced from the chamber through the liquid outlet means, said head having a bore one end of which provides a pressure fluid inlet, the other end of the bore being in communication with said chamber, said head having a passage communicating with said chamber and with said bore between the ends of said bore, and a spring pressed 5 valve within said bore having means for establishing communication between said passage and the inlet end of said bore, said valve when moved by live pressure due to a reduction in pressure in said chamber, momentarily closing said passage.
15. A pump embodying a chamber having a head and a check-valved liquid inlet, said head having a liquid outlet and a pressure fluid outlet, means for closing the pressure fluid outlet, means for moving said means to open position when the liquid has been forced from the chamber through the liquid outlet, said head having a vertical bore, the upper end of which provides a pressure fluid 25 inlet, said head having a passage extending from the lower end of said bore to said chamber and having a second passage com-
- municating with the chamber and with said bore between the ends thereof, a spool valve 35 slideable loosely within said bore and having a groove to register with the second passage and the passage extending from its upper end to said groove, and a spring seated within said bore for supporting said valve.
16. A pump embodying a chamber having a check-valved liquid inlet, a pressure fluid inlet and a pressure fluid outlet, yieldable means having a liquid outlet, a valve for automatically closing the pressure fluid outlet when the liquid level rises to a predetermined point in said chamber and adapted to be held in closed position by pressure fluid, a valve for closing the liquid outlet when the liquid level is lowered to a point near the liquid outlet, and means operated by said yieldable means for moving the first mentioned valve to open position out of range of the pressure fluid flowing through the pressure fluid outlet when the second mentioned valve closes the liquid outlet, said yieldable means being movable by pressure fluid when the liquid outlet is closed.
- In testimony that I claim the foregoing as my own, I have hereto affixed my signature in the presence of two witnesses. 60
